UNITED STATES PATENT OFFICE.

BRUNO POHLMANN, OF SIEMENSSTADT, NEAR BERLIN, AND ARTHUR CLAUSING, OF BERLIN-CHARLOTTENBURG, GERMANY, ASSIGNEES TO SIEMENS & HALSKE, AKTIENGESELLSCHAFT, OF SIEMENSSTADT, NEAR BERLIN, GERMANY, A CORPORATION OF GERMANY.

TELEPHONE INSTALLATION.

Application filed July 15, 1921, Serial No. 484,949, and in Germany October 31, 1919.

Our invention relates to telephone installations and more especially to an amplifying connection for use in installations. We are aware that such connections have 5 already been proposed in which a device serving to amplify the speaking current is arranged within the line, always one for each speaking direction, and which moreover are adapted to be interconnected for 10 the speaking direction required by means of switch relays in such a manner that for the duration of a conversation always only the amplifier appertaining to the speaking direction entering into consideration for the time 15 being will be interconnected. As the speaking direction changes there likewise takes place a change of the amplifier interpolated into the line. For the purpose of controlling the switch relays use is made of alternating current relays (oscillation relays) 20 which are arranged within the battery circuits of the switch relays and which are controlled by the speaking currents in such a manner that they will either close or open 25 the circuit of the relay to be actuated, according to the method of connection provided.

However, the drawback involved in the use of switch relays of the aforesaid description resides in various mechanical switch operations taking place successively before the spoken words are able to pass from the one section of the line into the other. The result is that in general after every break in 30 the conversation the first syllable of the next following word will be lost. This drawback evidences itself in a particularly annoying manner whenever a plurality of amplifying connections of the said kind are 35 inserted in the line. In addition, oscillation relays require an exceptionally careful watching and adjustment.

The aforesaid defects caused as aforesaid by the mechanical switch operations, are 40 remedied in accordance with our invention by reducing the number of the switch relays or even eliminating these latter entirely, by 45 not subsequently interconnecting the amplifiers by mechanical switch operations into the line, but by arranging them in the line 50 permanently, whereby they are merely adapted to be alternately brought into the operative position by fluctuations of the

grid potential created by rushes of current, whereas when they are in a state of rest the 55 grid potential is so dimensioned that the in-coming speaking currents will be as powerfully or still more powerfully damped by the amplifier in its inoperative state than they will be amplified when the said amplifier assumes its operative position. For the 60 purpose of operating the amplifiers there are arranged in accordance with our invention for each speaking direction a ready-working directing amplifier which is adapted to inter- 65 connect by means of the speaking currents arriving from the respective direction, the working voltage into the grid circuit of the appropriate speech amplifier, while simultaneously rendering the other directing am- 70 plifier appertaining to the opposite speaking direction inoperative by potential dis- placement in front of its grid.

The control of the speech amplifier is ef- 75 fected by the potential difference, obtained through the drop of voltage on the part of the anode current of the directing amplifier along a resistance inserted in the anode current. In order to secure only gradual 80 fluctuations of voltage of slight amplitude at the grid of the speech amplifier there is connected, in accordance with our invention, a suitable compensating condenser in parallel with the resistance. The reversing 85 speaking currents are preferably amplified before passing into the directing amplifier, in which case the degree of amplification and the compensating condenser are so dimensioned that the directing amplifier will per- 90 manently produce a displacement of poten- tial at which the speech amplifier will operate within the linear amplifying area. We have found it to be of advantage to render the control voltage, derived from the anode 95 circuit of the directing amplifier, adjust- able in order to be able to adapt it to any difference in the tubes when replacing these latter.

Having regard to the fact that during a 100 conversation the individual words transmitted supply the control device with alternating currents of varying amplitude, the possibility exists that the directing amplifier in accordance with the varying intensity of the control currents, might produce 105 different displacements of potential which

again might under certain circumstances cause a distortion of speech. Such a distortion will, however not arise when the displacement of potential fluctuates slowly for 5 a time and only to such an extent that the speaking waves at the speech amplifier will always be disposed within the range of the linear portion of the amplifying characteristic (characteristic of the grid voltage-10 anode current). The feature of causing only momentarily slow fluctuations to arise is realized by the compensating condenser. Besides, in order to render the displacement of potential independent of the strength of 15 the speaking currents, we have found it expedient to operate the directing amplifier permanently with saturation current, i. e. to so select the preliminary amplifying devices that the same amplifying currents will be 20 present both for the feebler speaking currents as well as for the more powerful ones.

Now it has been discovered that even in the case of such systems of electric connection where no mechanical control relay is 25 made use of, there will still be lost certain portions of the first syllables of words transmitted when a change in the direction of the conversation occurs and it has further been found that this defect is attributable to 30 a rise in the drop of voltage at the control resistance. The cause for this must be sought in the fact that the condenser connected in parallel to the control resistance will, when not charged, offer only a slight 35 resistance to the current impulses at the commencement of a wave train. In fact the condenser practically short-circuits the resistance so that as a result the drop of voltage cannot fully develop.

Now this defect is remedied in accordance 40 with our invention by replacing the condenser by an oscillating element composed of capacity and induction tuned to the frequency of the alternating current and interconnected into the secondary circuit in such 45 a manner that the entire combination of the connecting elements employed (i. e. controlling resistance, capacity and inductance) for the component of the continuous current appertaining to the secondary circuit will possess the nature of an ohmic resistance.

In the drawings affixed to this specification and forming part thereof, various modifications of an amplifying connection embodying our invention are illustrated in a 55 purely diagrammatic manner by way of example. In the drawings—

Fig. 1 discloses an amplifying connection 60 provided with a set of amplifiers for each line section, and

Figs. 2 to 6 disclose different systems of connection adapted to prevent the loss of the first syllables in the transmission of the voice after a break in the conversation.

Referring to Fig. 1, there are arranged in

the section F_1 of a long-distance line a speech amplifier R_1 and a directing amplifier R'_1 , an additional amplifying device R''_1 being inserted in front of this latter. The said section of the long-distance line is 70 inductively coupled by means of a pre-translator V_1 to the speech amplifier R_1 and by a pre-translator V'_1 to the amplifier R''_1 . Within the anode circuit of the directing amplifier there is located a resistance W_1 75 with which a condenser C_1 is connected up in parallel. For the long-distance line section F_2 , there are provided glow cathode tubes R_2 , R'_2 , R''_2 , correspondingly arranged in exactly the same manner as those in the 80 case of line section F_1 . To the ends of resistance W_1 , within the anode circuit of the directing amplifier R'_1 , are connected the grid circuits of the speech amplifier R_1 and of the set of directing amplifiers R''_2 , R'_2 , R''_2 . 85 In a similar manner the grid circuits of the speech amplifiers R_2 and of the set of directing amplifiers R'_1 , R''_1 are connected up to the ends of the resistance W_2 . In the place of a plurality of individual batteries, 90 use is made as far as practicable of common batteries for the several amplifying tubes.

The manner of operation of the above-described amplifying connection is as follows:

The speaking currents arriving across the long-distance line F_1 flow, on the one hand, into the amplifier R_1 and, on the other hand, into the set of amplifiers R''_1 , R'_1 . The speech amplifier R_1 is, however, at this junction inoperative and passes the in-coming speaking currents on after powerfully damping them. On the other hand, the speaking currents are powerfully amplified within the set of directing amplifiers, while within the anode circuit thereof there is produced a diminution of the pulsations of the pulsating continuous current by the condenser C_1 , and which continuous current brings about a change in the drop of voltage at the 100 ends of the resistance W_1 , causing such a displacement of potential to take place at the grid of the speech amplifier R_1 that this latter will now become operative and will begin to function within the linear amplifying area. Resistance W_1 is preferably 105 arranged to be adjustable, so that on replacing or renewing the rectifier, the resistance may be adjusted to the same voltage drop. The duly amplified speaking current is transmitted by the directing amplifier R_1 to the long-distance line section F_2 .

The voltage drop at the resistance at the same time causes a displacement of potential at the grids of R''_2 , R'_2 , and by these means 110 renders them inactive in order to prevent the amplified current, now passing on to line section F_2 , from causing—by means of the control arrangement (R'_1 , R''_2 , R''_2)—the speech amplifier R_2 to become operative. 115

For if such a contingency should arise the result would be that disturbances (howling) would arise within the speech amplifiers connected in series and now in readiness to operate, owing to re-coupling.

As soon as the subscriber connected up to the long-distance line section F_1 stops talking, the condition of the several portions of the circuit returns to normal while 10 now the subscriber connected up to line section F_2 is in his turn enabled to transmit a communication across the speech amplifier R_2 into the long-distance line section F_1 , in the very same manner as the subscriber connected up to line section F_1 had previously done.

However, instead of employing directly the potential differences prevailing at the resistances W_1 and W_2 , a relay may be interconnected into the anode circuit of the 20 directing amplifier adapted to apply a suitable battery to the grid circuits entering into consideration.

The directing amplifiers need not be arranged at the same place, as the speech amplifiers. Under certain conditions it may even prove expedient in order to reduce the influence of disturbing currents to arrange 25 the control elements (R'_1 , R''_1 and R'_2 , R''_2 respectively) appertaining to the two subscribers in the vicinity of the telephone stations.

In Figs. 2 to 6 there are disclosed several 30 systems of connections adapted to prevent the loss of the first syllables in the transmission of the voice after a break in the conversation.

In the form of connection disclosed in Fig. 2, the in-coming alternating current 35 impulses, after having already passed, it may be, through an amplifying connection are transmitted by a translator U to the grid circuit of a directing amplifier within the anode circuit of which there is arranged an ohmic resistance W . The voltage for 40 the relay coil or for the displacement of potential at the grid of the speech amplifier is derived from the ends of the resistance. In accordance with our invention there is 45 provided a shunt to this resistance comprising the capacity C and the inductance L which elements are tuned to the frequency 50 of the alternating control current.

In this arrangement, the alternating current 55 passes without encountering any notable resistance, through the shunt, whereas—owing to the counter-electromotive force of the inductance and which is at its maximum when the current first begins to flow—the 60 capacity is unable to absorb any appreciable quantity of continuous current. As a result, the voltage at the control resistance rapidly attains the value required.

In the form of connection disclosed in 65 Fig. 3, capacity C and inductance L are

connected in parallel to each other and in series with the control resistance W within the anode circuit. In this case, the oscillating circuit—provided the ohmic resistances and the time-constants of both branches 70 of the circuit are equal—acts after the manner of an ohmic resistance for continuous current. In case of resonance, the impedance for alternating current is represented by the formula 75

$$R_2 = \frac{\alpha^2 L^2}{R},$$

where α stands for the frequency of the circuit, L for the inductance and R for the ohmic resistance. Hence, the said oscillating circuit acts in the case of an alternating current like a real ohmic resistance which, by keeping R low, may be raised to a very high value, so that practically speaking no alternating current can any longer flow through. In this case, the voltage drop at the control resistance will take place almost 80 instantaneously.

Fig. 4 discloses another system of connection. A resistance W_1 , preferably equal in size to the control resistance W , is connected up in parallel with the latter, while intermediate the two there is inserted an oscillating circuit similar to the one shown in Fig. 3. In this arrangement, the alternating current—even in the case the resistance of the oscillating element is not extraordinarily high for said current—will take its 90 course almost exclusively through the resistance W_1 , whereas the continuous current will pass in two approximately equal halves through the two ohmic resistances.

Whenever it is a case of alternating currents of different frequency, such, for example, as a speaking current, then—when employing the system of connection disclosed in Fig. 2—a plurality of such tuning element combinations L , C will be connected in parallel with each other within the secondary circuit, as disclosed in Fig. 5, so that the several different frequencies existing in the several branches, will be distributed over the frequency range entering into consideration. Again, when making use of the form of connection shown in Fig. 3, a number of oscillating circuits, consisting of capacity and inductance, and tuned to different frequencies, will be connected in series within the anode circuit, as illustrated in Fig. 6. This is required for the reason that the impedance of the circuit will become very much smaller even at already comparatively slight deviations of the frequency from the resonance value. The connection shown in Fig. 4 may be proceeded with in exactly the same manner. By employing suitable selecting connections there is in addition provided the possibility of selecting a limited frequency area even 100 105 110 115 120 125 130

where a large frequency area prevails for the alternating control current, and of only employing this said limited area for control purposes. The secondary circuit may then 5 be operated by aid of a smaller number of oscillating elements.

What we claim is:

1. In combination, two two-way telephone lines, a thermionic speech amplifier for each 10 of said lines, each of said amplifiers comprising a cathode, a grid, and a plate and having its grid circuit connected to its own line and its plate circuit connected to the other line, the normal potential of the grid 15 being chosen such that the speech amplifier is inoperative at that potential, a thermionic directing amplifier for each line having its grid circuit connected therein, an ohmic resistance disposed in the plate circuit of each 20 directing amplifier, each resistance being also disposed in the grid circuit of the appertaining speech amplifier, such that when speech is transmitted across said long distance line the voltage drop in said resistance, caused by the amplified and rectified 25 speech currents flowing in the plate circuit of the directing amplifier, will increase the grid potential of said speech amplifier to render the latter operative.
- 30 2. In combination, two two-way telephone lines, a thermionic speech amplifier for each of said lines, each of said amplifiers comprising a cathode, a grid, and a plate and having its grid circuit connected to its own 35 line and its plate circuit connected to the other line, the normal potential of the grid being chosen such that the speech amplifier is inoperative at that potential, a thermionic directing amplifier for each line, having 40 its grid circuit connected therein, a resistance disposed in the plate circuit of each directing amplifier, each resistance being also disposed in the grid circuit of the appertaining speech amplifier and in the grid 45 circuit of the directing amplifier appertaining to the other long distance line, such that when speech is transmitted across the first-mentioned long distance line, the voltage drop in said resistance, caused by the rectified 50 and amplified speech currents flowing in the plate circuit will change the grid potential of the speech amplifier of the first line to render said speech amplifier operative, and will change the grid potential of 55 said directing amplifier appertaining to the other long distance line to render said directing amplifier inoperative.
- 60 3. In combination, two two-way telephone lines, a thermionic speech amplifier for each of said lines, each of said amplifiers comprising a cathode, a grid, and a plate and having its grid circuit connected to its own line and its plate circuit connected to the other line, the normal potential of the grid 65 being chosen such that the speech amplifier
- is inoperative at that potential, a thermionic directing amplifier for each line, having its grid circuit connected therein, a resistance disposed in the plate circuit of each directing amplifier, each resistance being also disposed in the grid circuit of the appertaining speech amplifier and in the grid circuit of the directing amplifier appertaining to the other long distance line, a capacity connected in parallel to each resistance for the purpose of securing a gradual fluctuation of voltage at the ends of the resistance within the plate circuit of the appertaining directing amplifier, the voltage drop in said resistance, when speech currents are influencing the grid of said directing amplifier, serving to increase the grid potential of said speech amplifier so as to render the latter operative and to decrease the grid potential of said directing amplifier appertaining to the other long distance line so as to render said latter directing amplifier inoperative. 70
- 75 4. In combination, two two-way telephone lines, a thermionic speech amplifier for each of said lines, each of said amplifiers comprising a cathode, a grid, and a plate and having its grid circuit connected to its own line and its plate circuit connected to the other line, the normal potential of the grid being chosen such that the speech amplifier is inoperative at that potential, a thermionic directing amplifier for each line, having its grid circuit connected therein, a resistance disposed in the plate circuit of each directing amplifier and each 80 resistance being also disposed in the grid circuit of the appertaining speech amplifier, and an amplifier for each directing amplifier connected at its output side to the input side of its directing amplifier and at its input side to the appertaining line, said amplifier being adapted to amplify the reverse speaking currents before they pass into the directing amplifier so that this latter is operating with saturation for all alternating 85 currents occurring during the service. 90
- 95 5. In combination, two two-way telephone lines, a thermionic speech amplifier for each of said lines, each of said amplifiers comprising a cathode, a grid, and a plate and having its grid circuit connected to its own line and its plate circuit connected to the other line, the normal potential of the grid being chosen such that the speech amplifier is inoperative at that potential, a thermionic directing amplifier for each line, having its grid circuit connected therein, a resistance disposed in the plate circuit of each directing amplifier, and each 100 resistance being also disposed in the grid circuit of the appertaining speech amplifier and in the grid circuit of the directing amplifier appertaining to the other long distance line, an oscillatory unit, tuned to 105 the frequency of the incoming alternating 110
- 115 6. In combination, two two-way telephone lines, a thermionic speech amplifier for each of said lines, each of said amplifiers comprising a cathode, a grid, and a plate and having its grid circuit connected to its own line and its plate circuit connected to the other line, the normal potential of the grid being chosen such that the speech amplifier is inoperative at that potential, a thermionic directing amplifier for each line, having its grid circuit connected therein, a resistance disposed in the plate circuit of each directing amplifier, and each 120 resistance being also disposed in the grid circuit of the appertaining speech amplifier and in the grid circuit of the directing amplifier appertaining to the other long distance line, an oscillatory unit, tuned to 125 the frequency of the incoming alternating 130

- currents and consisting of a capacity and an inductance, said unit being located adjacent to said resistance and connected into the anode circuit of the directing amplifier, such that the entire combination of the elements forming the connections for the continuous current component of the alternating current rectified, possesses the nature of an ohmic resistance.
6. In combination, two two-way telephone lines, a thermionic speech amplifier for each of said lines, each of said amplifiers comprising a cathode, a grid, and a plate and having its grid circuit connected to its own line and its plate circuit connected to the other line, the normal potential of the grid being chosen such that the speech amplifier is inoperative at that potential, a thermionic directing amplifier for each line, having its grid circuit connected therein, a resistance disposed in the plate circuit of each directing amplifier, and each resistance being also disposed in the grid circuit of the appertaining speech amplifier and in the grid circuit of the directing amplifier appertaining to the other long distance line, an oscillatory unit tuned to the frequency of the incoming alternating currents and consisting of an inductance and a capacity, said unit being disposed in the anode circuit of the directing amplifier and in parallel to said resistance.
7. In combination, two two-way telephone lines, a thermionic speech amplifier for each of said lines, each of said amplifiers comprising a cathode, a grid, and a plate and having its grid circuit connected to its own line and its plate circuit connected to the other line, the normal potential of the grid being chosen such that the speech amplifier is inoperative at that potential, a thermionic directing amplifier for each line, having its grid circuit connected therein, a resistance disposed in the plate circuit of each directing amplifier appertaining to the other long distance line, a plurality of oscillatory units, whose natural frequencies are distributed over the frequency range of the incoming speaking currents, the said units being inserted in the plate circuit of each directing amplifier.
8. In combination, two two-way telephone lines, a thermionic speech amplifier for each of said lines, each of said amplifiers comprising a cathode, a grid, and a plate and having its grid circuit connected to its own line and its plate circuit connected to the other line, the normal potential of the grid being chosen such that the speech amplifier is inoperative at that potential, a thermionic directing amplifier for each line, having its grid circuit connected therein, an ohmic resistance disposed in the plate circuit of each directing amplifier, and each resistance being also disposed in the grid circuit of the appertaining speech amplifier, such that when speech is transmitted across a long distance line, the voltage drop in said resistance, caused by the amplified and rectified speech currents flowing in the plate circuit of the directing amplifier, will increase the potential of said speech amplifier to render this latter operative, and selective oscillatory units disposed in the anode circuit of the directing amplifier for selecting a definite narrow frequency range out of the range of speaking current frequencies for controlling purposes as described.
- In testimony whereof we affix our signatures.

BRUNO POHLMANN.
